UNITED STATES PATENT OFFICE

FREDERICK W. CUFFE, OF WAYNESBORO, VIRGINIA, ASSIGNOR, BY MESNE ASSIGNMENTS, TO EDISON GENERAL ELECTRIC APPLIANCE COMPANY, INC., OF CHICAGO, ILLINOIS, A CORPORATION OF NEW YORK

DESIGN FOR A STOVE

Application filed July 12, 1928. Serial No. 27,467. Term of patent 14 years.

To all whom it may concern:

Be it known that I, FREDERICK W. CUFFE, a citizen of the Dominion of Canada, residing at Waynesboro, Virginia, in the county of Augusta and State of Virginia, have invented a new, original, and ornamental Design for a Stove, as shown in the accompanying drawings and described in the following specification.

Figure 1 is a perspective view of a stove showing my new design, and

Figure 2 is a vertical section through the

mid-portion of the switch panel of the stove shown in Figure 1.

The panel indented at the top and offset at the bottom with its curved ends and symmetrical appearance serving to break the contour of the front of the stove and set off the switches contained thereon, is believed to be the dominant feature of my design.

I claim:

The ornamental design for a stove as shown and described.

FREDERICK W. CUFFE.
